Patented Apr. 30, 1918.

UNITED STATES PATENT OFFICE.

JOSEPH W. BERRYMAN, OF GARDENA, CALIFORNIA, ASSIGNOR OF ONE-HALF TO
M. A. SIMONS, OF GARDENA, CALIFORNIA.

SAW-HANDLE.

1,264,145.

Specification of Letters Patent. Patented Apr. 30, 1918.

Application filed May 13, 1916. Serial No. 97,350.

To all whom it may concern:

Be it known that I, JOSEPH W. BERRYMAN, a citizen of the United States, residing at Gardena, in the county of Los Angeles 5 and State of California, have invented certain new and useful Improvements in Saw-Handles; and I do hereby declare the following to be a full, clear, and exact description of the invention, such as will enable 10 others skilled in the art to which it appertains to make and use the same.

This invention relates to a saw handle, and the primary object of the invention is to provide a saw handle which is provided 15 with a recess interiorly thereof in which is positioned a bulb and a tube leading outwardly out of the lower edge of the handle, so that air passing out of the tube will enter the kerf formed by the saw blade for the 20 purpose of blowing the saw dust therefrom.

A further object of this invention is to provide a pivotally mounted member which engages a portion of the bulb for compressing the bulb for forcing air outwardly 25 through the tube into the saw kerf.

With the foregoing and other objects in view this invention consists in such novel features of construction, combination and arrangement of parts as will be hereinafter 30 more fully described, illustrated in the accompanying drawings and claimed.

In describing the invention in detail reference will be had to the accompanying drawings wherein like characters designate 35 like and corresponding parts throughout the several views, and in which:—

Figure 1 is a side elevation of the improved saw handle.

Fig. 2 is a section on the line 2—2 of 40 Fig. 1.

Fig. 3 is an edge view of the saw, and

Fig. 4 is a detail perspective view of the 45 pivoted member carried by the saw handle for compressing the air bulb.

Referring more particularly to the drawings, 1 designates the saw handle as an entirety, which is of the standard size and is made in halves, of pressed or cast material,

such as metal, wood or fiber, which halves or sections are connected to each other and to 50 a saw blade 2 by the usual type of set screws 3. The grip portion 4 of the handle 2 is provided with the chamber 5, which opens out of the inner side of the grip 4 and also with a channel 6 which communicates with 55 the chamber 5 and with the lower edge of the handle as shown at 6. A rubber bulb 7 is positioned within the chamber 5 and it has a tube 8 connected thereto which extends through the channel 6 and is provided 60 for guiding air from the bulb 7 through the channel and out through the opening 6, into the kerf formed by the saw blades 2, during the operation of the saw. A bulb compressing member 9 is pivotally connect- 65 ed as shown at 10 to the grip 4 of the saw handle and it is concavo-convex, having a concaved recess 11 for receiving a portion of the bulb 7 so that when the member 9 is moved inwardly by the fingers of the operator of the saw it will press the bulb 7, for forcing air out of the bulb through the tube 8. The lower end 12 of the member 9 70 has its side edges curved, as clearly shown in Fig. 4 of the drawing, and this curved 75 end extends into the chamber 5 as shown at 14 in Fig. 1 of the drawing. The point 12 extending into the chamber, prevents the outward pivotal movement of the member 9.

In reducing the invention to practice, cer- 80 tain minor features of construction, combination and arrangement of parts may necessitate alterations to which the patentee is entitled provided such alterations are comprehended within the scope of what is 85 claimed.

What is claimed is:—

A saw handle comprising a body portion having a channel opening outwardly at a point adjacent its attachment to a saw blade, 90 a hand grip on said body and having a recess communicating with the channel, a bulb positioned in the recess and a portion disposed exteriorly thereof, a tube connected to the bulb and extending through the channel, 95 and a concavo-convex member pivoted to the

hand grip and receiving the exposed portion of the bulb and adapted to compress said bulb upon movement thereof in the recess, said concavo-convex member having the side 5 edges of its free end curved and disposed in the recess to prevent outward pivotal movement from the recess.

In testimony whereof I affix my signature in presence of two witnesses.

JOSEPH W. BERRYMAN.
